UNITED STATES PATENT OFFICE.

JAY G. WEISS, OF MONTCLAIR, NEW JERSEY, ASSIGNOR TO GENERAL MOTORS CORPORATION, OF DETROIT, MICHIGAN, A CORPORATION OF DELAWARE.

QUENCHING APPARATUS AND PROCESS.

Application filed April 29, 1921. Serial No. 465,522.

To all whom it may concern:

Be it known that I, JAY G. WEISS, a citizen of the United States, residing at 63 Undercliff Road, Montclair, county of Essex, 5 and State of New Jersey, have invented certain new and useful Improvements in Quenching Apparatus and Processes, fully described and represented in the following specification, and the accompanying drawings, forming a part of the same.

This invention relates to a quenching apparatus and process for making hardened steel sleeves, such as are employed in the manufacture of roller-bearings to form a 15 cylindrical raceway upon a shaft or within the casing of the bearing.

Such sleeves when formed of steel are highly heated to harden them by quenching in a bath of cooling fluid, and when such 20 sleeves are made of sections of tubing they retain their shape fairly well during the process of hardening and subsequent reheating to temper them to the desired point. Sleeves may, however, be made more cheaply 25 by forming each one of a flat blank, rolled up with the ends of the blank in proximity, but such sleeves are not so capable of retaining a true cylindrical form when heated and quenched in the usual manner for hardening.

An object of the invention, therefore, is to provide an improved apparatus and process for hardening sleeves or the like without distortion. Another object is to provide 35 quenching apparatus which will effect a more rapid and uniform quenching than can be secured by dipping work pieces into a bath. Another object is to provide improved means for holding or clamping sleeves or the like during hardening and for quenching them immediately following 40 their clamping.

To these ends and also to improve generally upon devices of the character indicated my invention consists in the various 45 matters hereinafter described and claimed.

In the illustrated construction, the heated sleeves are received and held against distortion by a cylindrical plug or hub which 50 projects upwardly from an apertured base communicating with a source of cooling fluid such as oil. Each sleeve is clamped externally against the plug by radially movable clamp sections which are preferably 55 actuated by fluid pressure, and mechanism

is provided for automatically causing the cooling fluid to flow up over the sleeve as soon as it is clamped.

In the drawing, Fig. 1 is a side elevation of an apparatus employed in practicing the process; the apparatus is shown in the position where the work piece is clamped and quenched and with the air valve turned to effect the unclamping and with the cooling fluid turned off; Fig. 2 is a plan of the leveling-ring; Fig. 3 is a section of a sleeve with a plug or hub inside of the same and an ejector discharging the sleeve; Fig. 4 is a plan of the machine with the sleeve-clamping devices omitted at the nearer half of the center line; Fig. 5 is a plan of a blank to form the sleeve; Fig. 6 is an end view of the same; Fig. 7 is an end view of the sleeve formed by rolling the blank into a cylinder; Fig. 8 is a side elevation of the sleeve thus rolled; Fig. 9 is a plan of the clamping-ring; Fig. 10 is an edge view of the same; Fig. 11 is a plan of the clamp-sections; and Fig. 12 is an edge view of the same. Fig. 13 is a plan of the plug or hub; and Fig. 14 a side view of the same with the shank and cross-bar of the ejector. The apparatus is especially adapted for hardening a sleeve on one side.

The development of a sleeve from the blank is shown in Figs. 5 to 8 inclusive. Fig. 5 represents the blank *g* cut from sheet-metal of suitable thickness with tapering point *h* at one end and tapering notch *i* at the opposite end and, as shown in Figure 8, there is a space *h'* between the rolled up ends of the blank.

The machine has a plate *a* on the upper end of a trunk or cylinder *p* which contains a supply of cooling fluid, the cylinder *p* being mounted in a suitable tank to receive the overflow. The plate *a* supports the base *b'* of a guide ring *b* which surrounds the work piece and its clamping means and forms a treating chamber.

Four quadrant clamp-sections *c* are shown inside the guide-ring, each provided with a lug *d* fitted to play in a notch *d'* in the guide-ring. The lugs are held movably in the notches *d'* by a collar *d*² fixed to the guide ring *b*.

A plug or hub *f* is secured upon the base in the center of the guide-ring *b*, and the clamp-sections surround the hub at a sufficient distance to insert the sleeve *e*.

The clamping-ring *k* is fitted to slide vertically upon the outside of the guiding *b*, and is beveled outwardly to fit corresponding slopes or bevels upon the outer ends of the lugs *d*. Each of the clamp sections *c* embraces one quadrant of the plug *f* and the lifting of the clamping ring *k* operates to press all the clamp sections radially inwards upon the sleeve *e* by the action of the bevels on the clamping ring and on the ends of the lugs *d*.

Longitudinal spiral grooves *f'* are formed in the hub, leaving ridges *f''* which contact with the inner side of the sleeve, and grooves *c'* are formed longitudinally within the clamp-sections leaving ridges *c''* to contact with the outer side of the sleeve, see Fig. 13.

The base *b'* has a surface to support the end of the sleeve *e* and is provided with holes or passages *o* communicating with the cylinder *p*. The cooling fluid is maintained at or near the level of the passages *o* in readiness for instant flow upwardly over the sleeve, the fluid traversing the grooves *f'* and *c'* and overflowing into the tank. Holes *s* in the plug *f* also allow the fluid to rise up and flow over the end of the sleeve. The passage of the fluid over the work piece insures a more rapid and uniform cooling than when a work piece is merely dipped into a bath of unagitated liquid.

Springs *e* are inserted between the clamp-sections to hold them normally expanded within the guide-ring *b* when inserting the sleeve, as shown in Fig. 4.

The cylinder or trunk *p* has a branch *p'* with a valve *q* inserted in the same, and operated by a lever *r'*. The inlet to the valve *q* is supplied with cooling fluid under sufficient pressure, so that when the valve is opened the fluid flows through the trunk and the passages *o* up into the grooves *f'* and *c'*.

A spring *r* attached to the valve-lever *r'* tends to open the valve *q*, but a cord *s* is extended from the valve-lever *r'* to a crank-arm *s'* upon the spindle of the air-valve *n*, so that the valve *q* will be closed when the valve *n* is actuated to unclamp the work piece.

The clamp-ring is raised by toggle-links *l* actuated by connections to the piston-rod *m* of a piston in an air-cylinder *m'*. The movements of the piston and consequently of the toggle are governed by an air-valve *n* having a handle *n'* for shifting the same.

In Figure 1 the parts are shown in the position where the work piece has been clamped and quenched and with the valve *n* actuated to allow the toggle to subsequently release the work piece. In this position of the valve *n* and handle *n'*, the cord *s* pulls the lever *r'* to the right to close the valve *q* and cut off the supply of cooling

fluid. When, however, the handle *n'* is turned upwardly to open valve *n* and straighten the toggle, the cord *s* is slackened so that the spring *r* will open the valve *q* and immediately throw a flood of quenching fluid upwardly through the passages *o* and over the work piece. The lever *r'* is alternately locked and released by a pivoted button *n''* which is automatically actuated by a link *s''* from the toggle. 75

The sleeve is heated in the furnace and dropped by suitable tongs over the plug or hub, the top of which is tapered as shown in Figs. 1 and 14 to facilitate the application of the sleeve, and the sleeve is pressed downwardly upon the base *b'* by a levelling-ring *t* jointed at the side of one clamp-section and movable by means of a handle *f*.

This ring is thrown entirely clear from the plug or hub prior to applying the sleeve thereto, and immediately pressed downward upon the top of the sleeve, as shown in Fig. 1, to force it into close contact with the base *b'* before the air-valve is opened to operate the toggle and clamp the sleeve upon the hub. 80

When the sleeve is released by the bending of the toggle, an ejector *v* is actuated to push the sleeve upward for removal. 95 The ejector is formed as a cross-bar fitted movably to a transverse slot *u* in the lower part of the hub *f* and is elevated by a rod *w* and hand-lever *w'*, see Fig. 3.

The ends of the cross-bar project beyond the sides of the hub beneath the sleeve and thus lift the sleeve partially from the hub when the ejector is raised, so that the sleeve can be seized by tongs and removed. Holes *x* (see Fig. 1) are extended through the 100 perimeter of the base *b'* into the passages *o*, and corresponding holes *x'* are extended through the clamp-ring to register with the holes *x* when the clamp-ring is lowered, thus discharging the oil from the entire 110 interior of the clamping device down to the level of the holes *x*.

The cooling fluid remains at such level and is under such pressure upon the closing of the valve *q* that the oil flows immediately upward into the grooves and perforations of the hub as soon as the oil-valve is opened to chill the sleeve. 115

Having thus set forth the nature of the invention what is claimed herein is:

1. In a process for hardening steel sleeves, heating the sleeve to the desired temperature, clamping the heated sleeves by pressure from clamping-sections upon numerous points upon the periphery of the sleeve, supplying a current of cooling fluid to the said sleeve and forcing the current longitudinally within the sleeve. 125

2. A means for hardening steel sleeves, consisting of a stationary base, a longitudi- 130

nally channelled hub seated upon the said base and having a transverse slot in the lower part of the hub and extending upward to a point above the center of the hub, 5 clamping sections with means for moving them toward and from the hub and an ejector-rod movable vertically in a bore of the hub with an ejector crossbar fitted movably to the transverse slot and operating, 10 when desired, to eject the sleeve from the hub.

3. A means for hardening steel sleeves, consisting of a trunk having a stationary perforated base mounted thereon, said trunk 15 being provided with a branch and fluid supply-valve, a longitudinally channelled hub seated upon the said base its channels connecting with the perforations of the base, clamping sections fitted to clamp the sleeve 20 upon the hub, and an air-cylinder, with connections to the supply-valve and to the clamping sections for operating both simultaneously.

4. A means for holding steel sleeves while 25 hardening, consisting of a channelled hub to fit within the sleeve, internally channelled sections sustained movably about the said hub, a base supporting the hub with a guide-ring around the same, and a clamping-ring 30 movable upon the guide-ring with beveled face fitted to press the sections upon the exterior of the sleeve.

5. A means for securing a prompt flow 35 of cooling fluid to a heated sleeve when clamped, consisting of a channelled hub to fit within the sleeve, a perforated base supporting such hub, clamping sections to press upon the outer side of the sleeve, a trunk below the base supplying the cooling fluid 40 to the perforations of the base and the channels of the hub, the base having over-flow holes close to the bottom of the hub, whereby the oil is retained close to the bottom of the hub ready to be quickly discharged thereto when required.

6. A means for holding steel sleeves while 45 hardening, consisting of a channelled hub to fit within the sleeve, internally channelled sections sustained movably about the hub and provided with beveled lugs, a base supporting the hub with a guide-ring around the channelled sections, and a clamping-ring 50 fitted movably upon the guide-ring and having a beveled face to fit the lugs upon the sections, and a means, as a piston in an air-cylinder, for exerting an elastic pressure to move the clamping-ring against the beveled lugs, and thus maintaining a continued pressure upon the clamping sections during 55 the cooling of the sleeve.

7. In heat-treating apparatus, a treating 60 chamber, clamping devices therein, means for actuating said clamping devices, and means actuated by said clamp-actuating 65 means at its limits of movement for con-

trolling the flow of treating fluid to said treating chamber.

8. In heat treating apparatus, a treating 70 chamber, clamping devices in said chamber for holding a piece of work therein, means for actuating said clamping devices, a valve for controlling the flow of treating fluid to said treating chamber, and means controlled by said clamp actuating means to operate said valve for causing the treating fluid to 75 flow over said work-piece; substantially as described.

9. In apparatus of the character described, a stationary plug conforming to the 80 interior surface of a sleeve to receive and hold it in a fixed position, means for maintaining a supply of cooling fluid near the level of the sleeve, and means for raising the level of the fluid to cause a stream of cooling fluid to flow over said sleeve; sub- 85 substantially as described.

10. In apparatus of the character described, a stationary plug conforming to the 90 interior surface of a sleeve to receive and hold it in a fixed position, means for maintaining a supply of cooling fluid near the level of the sleeve, means for pressing the sleeve against the plug, and means for automatically causing a stream of cooling fluid 95 to flow over said sleeve when the latter is clamped; substantially as described.

11. In apparatus of the character described, a stationary base having fluid passages therein, a source of fluid supply supporting the base and having connection 100 with the passages, a cylindrical plug extending upwardly from the base for receiving and holding a sleeve in a fixed position upon the base, and means for causing a stream of fluid to flow from said source of supply to 105 said sleeve; substantially as described.

12. In apparatus of the character described, a stationary base having fluid passages therein and a surface to support the end of a sleeve, a plug extending upwardly 110 from the base for receiving and holding the sleeve in a fixed position upon the base, and a fluid supply and a valve for causing a stream of cooling fluid to flow through said passages in the stationary base and 115 over the sleeve; substantially as described.

13. In apparatus of the character described, a base having fluid passages therein, means for maintaining a supply of cooling fluid near the level of the passages, 120 means including slideable clamp sections for clamping a sleeve in a fixed position upon the base, and a valve controlled by the operation of the clamping means for causing a stream of cooling fluid to flow through 125 said passages and over said sleeve when the latter is clamped; substantially as described.

14. In apparatus of the character described, a base having fluid passages there- 130

- in, a plurality of clamp sections radially movable over the base towards and from the exterior surface of a sleeve supported on the base, and mechanism for operating said sections to clamp the sleeve and for thereafter directing a stream of cooling fluid through said passages and over said sleeve; substantially as described.
15. In apparatus of the character described, a base having fluid passages therein and a horizontal surface to support the end of a sleeve, a plurality of clamp sections movable against the exterior surface of said sleeve, means for operating said sections to clamp the sleeve in a fixed position on the base, and means for causing a stream of cooling fluid to flow through said passages in the base and over the sleeve; substantially as described.
16. In apparatus of the character described, a base having fluid passages therein and a surface to support the end of a sleeve, a plug on said base to hold the interior of the sleeve, means outside the sleeve to clamp it against the plug, and a fluid supply and a valve for causing a stream of cooling fluid to flow through said passages in the base and over the sleeve; substantially as described.
17. In apparatus of the character de-
scribed, a base having a surface to support the end of a sleeve, a plurality of clamp sections radially movable over the base against the exterior surface of the sleeve, a guide ring fixed to the base, and means 35
slidable on said guide ring for operating said sections to clamp the sleeve; substantially as described.
18. In apparatus of the character de-
scribed, a base having a surface to support 40 the end of a sleeve, a plurality of clamp sections radially movable over the base against the exterior surface of the sleeve, a guide ring fixed to the base, means 45
slidable on said guide ring for operating said sections to clamp the sleeve, and fluid pressure operated mechanism for sliding said means; substantially as described.
19. In apparatus of the character de-
scribed, a base to support the end of a 50 sleeve, a plug to hold the interior surface of the sleeve, said plug having a transverse slot through its lower portion, and a cross bar slidable in said slot and arranged to engage the end of the sleeve to eject the 55 latter from the plug; substantially as described.

In testimony whereof I have hereunto set my hand.

JAY G. WEISS.
